[57] CLAIM

The ornamental design for an applicator container, as shown and described.

DESCRIPTION

FIG. 1 is an exploded perspective view of an applicator container showing my new design;

FIG. 2 is a top plan view of the design shown in FIG. 1 in assembled form;

FIG. 3 is a front elevational view of the design shown in FIG. 1 in assembled form, the back of the container having the same appearance;

FIG. 4 is a side elevational view of the design shown in FIG. 3, the other side of the container having the same appearance; and

FIG. 5 is a bottom plan view of the design shown in FIG. 3.
